UNITED STATES PATENT OFFICE.

VICTOR H. JENNINGS AND HERBERT H. WATSON, OF WORCESTER, MASSACHUSETTS,
ASSIGNORS TO CROMPTON & KNOWLES LOOM WORKS, OF WORCESTER, MASSACHUSETTS, A CORPORATION OF MASSACHUSETTS.

WEFT-CONTROLLED LOOM-STOPPING MECHANISM.

Application filed July 2, 1926. Serial No. 120,227.

This invention relates to means for automatically stopping a multi-shuttle loom upon substantial exhaustion of weft or filling in either shuttle. The invention is more particularly designed for application to a loom in which two drop boxes are provided at one side of the loom and a single box at the other side of the loom.

It is the general object of our invention to provide weft controlled means for stopping the loom with the substantially exhausted shuttle at the single box side of the loom, in which position the shuttle may be easily removed and replaced.

A further object is to provide improved devices for preserving an indication of substantial weft exhaustion until the return of the indicated shuttle, in the event of a shuttle change immediately after indication.

Our invention further relates to arrangements and combinations of parts which will be hereinafter described and more particularly pointed out in the appended claims.

A preferred form of the invention is shown in the drawings in which

Fig. 1 is a plan view, partly in section, of our improved loom stopping mechanism;

Fig. 2 is a similar view, but showing the parts in a different position;

Fig. 3 is a sectional side elevation, taken substantially along the line 3—3 in Fig. 1;

Fig. 4 is a similar view, but taken along the line 4—4 in Fig. 2;

Fig. 5 is a detail sectional front elevation, taken along the line 5—5 in Fig. 2;

Fig. 6 is a perspective view of one of the indicating blocks or slides; and

Fig. 7 is a diagrammatic view, indicating the control of certain parts from the drop box mechanism.

Referring to the drawings, I have shown a portion of a loom frame 10 having the usual shipper shaft 11, shipper handle 12, and knock-off lever 13 mounted thereon. These parts are formed and connected in the usual manner, as shown for instance in the patent to McGuiness, No. 1,633,644, issued June 28, 1927, and in themselves form no part of my present invention.

Each shuttle S supports a bobbin B which is engaged by a weft detecting member or feeler 14, shown as of the usual "side-slip" type. The weft detector 14 is slidably mounted in a stand 15 adjustably secured on

a bracket 16 fastened to the front of the 55 loom frame 10.

The stand 15 is provided with a cross slide 17 which remains in the normal position shown in Fig. 1 so long as the detector 14 engages a bobbin B having a sufficient supply of weft thereon. When the weft becomes substantially exhausted, as indicated on the bobbin B' in Fig. 2, the detecting member 14 slips along the barrel of the bobbin B' toward the tip, carrying with it the slide 17 60 and also an indicating member 18 connected thereto, the function of which will be hereinafter explained.

A stand 20 is secured to the loom frame 10 and is provided with ribs or guide-ways 21 70 for a slide 22. A stud 23 extends through a slot 24 (Fig. 3) in the slide 22 and acts as a pivot for the slide, while at the same time permitting sliding movement thereof.

The slide 22 has a notch or recess 25 (Fig. 75 1) which receives one end of a lever 26 pivoted at 27^a on a stand 20 and engaging the knock-off lever 13. When the slide 22 is pushed forward, the knock-off lever 13 is pushed rearward, releasing the shipper lever 12, and causing the loom to come to rest.

In its rear portion, the slide 22 is provided with transversely extending slots or 80 guide-ways 27 and 28 for upper and lower indicating blocks 30 and 31. When the slide 22 is in the position indicated in Figs. 3 and 5, the upper indicating block 30 is aligned with the reversed upper end 18^a of the indicating member 18 which is slidable in a transverse opening in the stand 20. 90

The normal position of the block 30 is at the extreme left, corresponding to the position of the block 31 in Fig. 5, but if the indicating member 18 is moved to the right by the detector 14, as shown in Fig. 2, the block 30 will also be moved to the right to the position shown in Fig. 5. If the slide 22 is raised, as shown in Fig. 4, and the indicating member 18 is moved to the right, the lower block 31 will be engaged thereby and 95 will be moved to the right. 100

The shape and appearance of the blocks 30 and 31 is indicated in Fig. 6, from which it appears that each block has a wide portion at one end and a narrow portion at the other end and that a slot 32 is provided on the under side of each narrow portion. A stud 33 is also provided on top of each block. 105

The slide 22 is positioned vertically by a lifter rod 35 (Fig. 3) having a forwardly offset head 36 underlying a shoulder 37 (Fig. 5) at the side of the slide 22.

5 The lifter rod 35 may be actuated in any convenient manner from the drop box or pattern mechanism of the loom and we have indicated in Fig. 7 one such connection, comprising a cord 38 connected at one end to the drop boxes 39 and extending around a guide-pulley 40 to a bell-crank 41 which in turn is connected to the lifter rod 35.

An actuating member 43 (Fig. 3) is mounted upon a fixed pivot 44 and is connected by a link 45 to a lever 46 which is raised by a cam (not shown) on the bottom shaft of the loom once for every two picks of the loom.

The actuating member 43 is recessed at 47 20 so that said member will engage only one of the slides 30 or 31 at the same time. The actuating member 43 may engage the block 30 when the slide 22 is in lowered position and may engage the block 31 when the slide 25 is in raised position. The range of movement of the actuating member 43 is limited, so that it will not engage the block 30 or 31 in the narrow portion thereof but will only engage a block when it is moved to the 30 right to the position of the block 30 in Fig. 5, in which event it will engage the wide end portion of the block and will thus force the slide 22 forward, swinging the lever 26 and operating through the knock-off lever 13 35 to stop the loom.

Light springs 50 (Fig. 2) normally hold the blocks 30 and 31 in their left hand position unless moved therefrom by the indicating member 18. When a block is moved to 40 the right by the indicating member, the notch 32 of the block will engage the right hand guide or rib 21 of the stand 20, thus retaining the block in right hand or operative position until the slide 22 approaches 45 its extreme forward position, at which point the projecting end of the block 30 or 31 engages a cam-lug 51 on the stand 20, which raises the block so that it is released and will be returned to its inoperative position by its 50 spring 50.

Having described the details of construction of our loom stopping mechanism, the method of operation thereof will be readily understood. Under normal operating 55 conditions, both indicating blocks 30 and 31 remain in their left hand positions, as viewed in Fig. 1, and the actuating member 43 can move freely forward without engaging either blocks. If the bobbin in the 60 shuttle corresponding to the upper drop box 39 becomes substantially exhausted, the block 30 will be moved to the operative position indicated in Fig. 5.

The parts are so timed that the indicated 65 shuttle will be picked to the drop box side

of the loom after its block 30 is thus positioned. The actuating member 43 will then move forward as the indicated shuttle is about to be returned to the single box side of the loom, and the loom stopping mechanism 70 will stop the loom with the lay approaching front center, and with the substantially exhausted shuttle at the single box side of the loom, which is the most convenient point at which to remove and replace a shuttle. 75

If the boxes are changed before the indicated shuttle returns to the single box side of the loom, the slide 22 will be raised or lowered so that the block 30 or 31 corresponding to the exhausted shuttle will no 80 longer be aligned with the actuating member 43, although the block will be held in its indicated or operative position by engagement of its notch 32 with the rib 21 at the side of the stand 20. The actuating member 43 will thus remain inoperative until the boxes are again shifted to bring the exhausted shuttle to running position. Such movement will raise or lower the slide 22, returning the indicated block 30 or 31 to position for engagement by the actuating member 43 which will thereupon stop the loom. 85 90

We have thus provided effective mechanism for preserving an indication of weft exhaustion until the indicated shuttle is 95 about to be returned to the single box side of the loom. Obviously the invention could be adapted to three or more shuttles by adding more indicating blocks on the slide 22.

Having thus described our invention and 100 the advantages thereof, we do not wish to be limited to the details herein disclosed otherwise than as set forth in the claims, but what we claim is:—

1. In a loom having a plurality of drop 105 boxes at one side of the loom and a single box at the other side, in combination, a weft detector, loom stopping mechanism, an actuator for said stopping mechanism, an indicating element for each shuttle effective to render said actuator operative to stop the loom, and connections whereby said elements are operatively positioned by said weft detector.

2. In a loom having a plurality of drop 115 boxes at one side of the loom and a single box at the other side, in combination, a weft detector, loom stopping mechanism, an actuator for said stopping mechanism, an indicating element for each shuttle effective to 120 render said actuator operative to stop the loom, connections whereby said elements are operatively positioned by said weft detector, and means to hold an indication of weft exhaustion until the exhausted shuttle returns 125 to running position.

3. In a loom having a plurality of drop 130 boxes at one side of the loom and a single box at the other side, in combination, a weft detector at the single box end of the loom,

and loom stopping mechanism controlled thereby, said stopping mechanism being effective to stop the loom on the first return of the indicated shuttle to the single box side of the loom after indication of weft exhaustion, said mechanism being held inoperative with respect to said indicated shuttle until such return thereof.

4. In a loom having a plurality of drop boxes at one side of the loom and a single box at the other side, in combination, a weft detector, loom stopping mechanism, an actuator for said stopping mechanism, and connections between said actuator and said stopping mechanism controlled by said detector and also controlled in definite relation to the movements of the drop boxes.

5. The combination in a loom as set forth in claim 4, in which said connections include a separate indicating element for each shuttle, selectively positioned by said weft detector.

6. The combination in a loom as set forth in claim 4, in which said connections include a separate indicating element for each shuttle selectively positioned by said weft detector, and a movable support for said indicating elements, movable in definite relation to the movements of the drop boxes.

7. The combination in a loom as set forth in claim 4, in which said connections include a separate indicating element for each shuttle, selectively positioned by said weft detector, and means to reset said indicating element to inoperative position as the loom is stopped.

8. The combination in a loom as set forth in claim 4, in which said connections include a separate indicating element for each shuttle, selectively positioned by said weft detector, and means to retain said indicated element in operative position until the loom is stopped.

9. In a loom having a plurality of drop boxes at one side of the loom and a single box at the other side, in combination, a weft detector, loom stopping mechanism, an actuator for said stopping mechanism, and con-

nnections between said actuator and said stopping mechanism controlled by said detector and also controlled in definite relation to the movements of the drop boxes, through which connections the loom is stopped only upon the return of the indicated shuttle to the single box side of the loom.

10. In a loom having a plurality of drop boxes at one side of the loom and a single box at the other side, in combination, a weft detector mounted at the single box side of the loom, loom stopping mechanism, an actuator, a pivoted slide mounted in the path of the actuator, and indicating elements transversely movable in said pivoted slide, said elements being selectively moved to position to render said actuator operative upon indication of substantial weft exhaustion in the corresponding shuttle.

11. In a loom having a plurality of drop boxes at one side of the loom and a single box at the other side, in combination, a weft detector, loom stopping mechanism, a member connected therewith and mounted for vertical adjustment in accordance with the movements of the drop boxes, indicating elements therein controlled by the weft detector, and an actuator rendered effective by said indicating elements to move said member and stop the loom when one of said indicating elements is placed in operative position.

12. In a loom having a plurality of drop boxes at one side of the loom and a single box at the other side, in combination, a weft detector at the single box side of the loom, mechanism effective to stop the loom upon return of the indicated shuttle to the single box side of the loom, and means controlled in definite relation to the movements of the drop boxes effective to delay the operation of said stopping mechanism until said indicated shuttle returns to said single box.

In testimony whereof we have hereunto affixed our signatures.

VICTOR H. JENNINGS.
